LAWN EDGER OR SIMILAR ARTICLE

Fred R. Pering, Benton Harbor, Mich.

Application April 12, 1955, Serial No. 35,482

Term of patent 14 years

(Cl. D40—1)

Figure 1 is a side elevational view of a lawn edger or similar article showing my new design with a handle structure indicated generally in broken lines;

Figure 2 is a side elevational view thereof as the same appears from the reverse side thereof;

Figure 3 is a top plan view of the same; and

Figure 4 is a vertical cross sectional view of the same to show the general contour thereof as it appears substantially along the plane of the line 4-4 in Figure 2.

The characteristic features of the design reside in the portions shown in full lines.

I claim:

The ornamental design for a lawn edger or similar article, substantially as shown and described.
